Primary Examiner — Shawn T Gingrich(74) *Attorney, Agent, or Firm* — Dickinson Wright PLLC(57) **CLAIM**

The ornamental design for an electronic connector, as shown and described.

DESCRIPTION

FIG. 1 is a perspective view of the electronic connector;

FIG. 2 is a top view thereof;

FIG. 3 is a bottom view thereof;

FIG. 4 is a left side view thereof;

FIG. 5 is a right side view thereof;

FIG. 6 is a front view thereof; and,

FIG. 7 is a rear view thereof.

The broken lines in the drawings illustrate portions of the electronic connector housing that form no part of the claimed design.
